(57) **CLAIM**

The ornamental design for a headlight for a vehicle, as shown and described.

DESCRIPTION

This application contains subject matter related to the following co-pending U.S. design patent application:

Application Ser. No. 29/739,865, filed herewith and entitled “Headlight for a Vehicle”.

FIG. 1 is a front view of a headlight for a vehicle according to the design;

FIG. 2 is a right side perspective view thereof;

FIG. 3 is a right side view thereof; and,

FIG. 4 is a top view thereof.

The broken lines in the drawings depict portions of the headlight for a vehicle and form no part of the claimed design. The additional broken lines in the drawings illustrate environmental subject matter only and form no part of the claimed design. The drawings and descriptions represent the right side embodiment. The claim is also for a mirror image left side embodiment that is not shown.
